(57) **CLAIM**

The ornamental design for a display screen with graphical user interface or portion thereof, as shown and described.

DESCRIPTION

FIG. 1 is a front view of a display screen with graphical user interface or portion thereof, according to a first embodiment; and,

FIG. 2 is a front view of a display screen with graphical user interface or portion thereof, according to a second embodiment.

The outermost broken line rectangle showing of the display screen in FIG. 1, and all other broken lines showing portions of the graphical user interface in FIGS. 1-2 are included for the purpose of illustrating portions of the article and form no part of the claimed design. In FIG. 2, the perimeters of the portion of the underlying display screen and the graphical user interface are understood to be flush.
